(57) **CLAIM**

The ornamental design for a switchblade divot repair tool, as
shown and described.

DESCRIPTION

FIG. 1 is a perspective view showing the top and right side
of the switchblade divot repair tool showing my new design.

FIG. 2 is a top view thereof.

FIG. 3 is a right side view thereof.

FIG. 4 is a left side view thereof.

FIG. 5 is a bottom view thereof.

FIG. 6 is a top view thereof.

FIG. 7 is a back view thereof; and,

FIG. 8 is a perspective view of FIG. 1, the divot repair tool
blade shown extended.
